C. J. HAGSTROM

DOUBLE ACTING DOOR LATCH

Filed May 20, 1927

Inventor: C. A. Hagstrom
By his attorney Bro. L. Beeler

UNITED STATES PATENT OFFICE.

CARL JOHN HAGSTROM, OF GLEN COVE, NEW YORK.

DOUBLE-ACTING DOOR LATCH.

Application filed May 20, 1927. Serial No. 192,823.

This invention relates to builders' hardware and has particular reference to catches or latches for a plurality of doors or other similar openings.

In numerous instances there are places where a pair of doors are provided for passage ways from one room or space to another, and one of the objects of the invention is to render it impossible for both of such doors to be opened at the same time, or for either door to be opened while the other is open. In places such as hospitals, laboratories, or the like, where photographic developments are being made, or X-ray developments are being pursued, it is of utmost importance that the amount of light permitted to enter a room or space shall be as small as possible, and consequently this device insures that when two doors are provided, either of which may be used freely to the exclusion of the other, they may not be opened or be open at the same time.

With the foregoing and other objects in view the invention consists in the arrangement and combination of parts hereinafter described and claimed, and while the invention is not restricted to the exact details of construction, disclosed or suggested herein, still for the purpose of illustrating a practical embodiment thereof reference is had to the accompanying drawings in which like reference characters designate the same parts in the several views, and in which—

Figure 1 is a side elevation of a preferred embodiment of the invention, both doors being shown as being held normally locked closed.

Fig. 2 is a similar view showing the position of the parts with one of the doors open, and with the other locked positively from being opened until the previously open door is returned to normal locked position.

Fig. 3 is a diagram indicating a suggestion of a pair or group of doors such as are referred to herein.

Fig. 4 is a view of a modification of keeper mechanism.

It will be understood that the doors may be variously designed as to their construction and direction or mode of operation, but each of the doors carries a catch 10 which when the door is being closed has wiping contact at 11 with a catch bolt 12 slidable against the force of a spring 13 in a direction transverse to the direction of movement of the catch 10.

The bolt 12 is provided with a slot 14 within which is housed the spring 13, the spring having abutment at one end against one end of the slot and at the other end against a fixed guide pin 15 carried by a tumbler or actuator 16 pivoted at 17. A strong leaf spring 18 is anchored at 19 and 20 and exerts a normal tendency to keep the tail piece 16^a of the tumbler against a stop or abutment 21 fixed to the casing.

22 indicates a member slidable along a pair of fixed guide ways 23 carried by the casing, the ends of which in normal position lie adjacent to and slightly overlap the path of movement of the ends 16^a of the tumblers 16. The adjacent ends 16^a of the tumblers and 22^a of the keeper 22 are beveled or rounded so that either of the ends 16^a when swung downward or away from the abutment 21 may cause, by wiping contact with the keeper, the endwise movement of the keeper along the guides 23. The amount of overlap or eccentricity of the two ends 16^a and 22^a is sufficient during such movement of one of the tumblers to cause the opposite end of the keeper 22 to assume a position well beneath the end 16^a of the opposite tumbler as shown at 22^b in Fig. 2, rendering it impossible for the opposite door to be opened until the keeper is restored again to its normal position as in Fig. 1.

At 24 I show a link having one end or tooth 25 fitted in a notch 26 in the keeper 22. This link is pivoted at 27 adjacent to its opposite end having a similar tooth connection at 28 in a notch 29 of a trip bar 30 slidable parallel to the keeper 22 in guides 31 fixed to the casing. The length of the bar 30 corresponds approximately to the normal space or gap between the catches 10 of the two doors when they are closed.

Having thus set forth the mechanical construction, the mode of operation may be briefly summarized as follows: With the doors closed and held closed by the catches as shown in Fig. 1, either door may be opened by direct pull or push as, for instance, as shown at the left end of Fig. 2. The catch 10 carried by said door will cause, by its co-operation with the parts 11 and 12, the rocking of the tumbler 16 in a clockwise movement as above described, the end 16^a thereof wiping against the end 22^a of the keeper causing the endwise bodily projection of the keeper to the position of Fig. 2. This movement of the keeper, acting through the link 24, causes a

similar movement in the opposite direction of the bar 30 toward the open door, but to a shorter distance than is represented by the movement of the keeper. Consequently the 5 end of the trip bar adjacent to the open door is caused in this manner to lie in the path of the catch 10 when the open door again comes shut. The movement of the keeper 22 in the manner just described bringing its end 22^a 10 positively beneath the end 16^a of the opposite tumbler, constitutes a positive stop or barrier preventing the opening of the second door, while the first door is open. When, however, the open door is returned to closed position, 15 the catch 10 thereof impinging against the end of the bar 30, will cause through the rocking of the link 24, the return to normal position of the keeper 22, making it then possible for either door to be opened 20 in the regular way. It will be noted, however, that should it be undertaken to open both doors at the same time, the ends of the keeper will both bar the movement of the tail pieces 16^a of the tumblers and render it im- 25 possible for either of the doors to be opened at such time. When an open door is returned to closed position, the surface 11 of its keeper 10 wipes against the beveled end of the bolt 12 and causes the bolt to pass out of the way 30 of the catch, but the spring 13 promptly returns the bolt to normal holding position as soon as the catch 11 passes the point thereof.

The description of construction and operation of the latching mechanism for either 35 door will be understood as applicable to both because as shown herein the mechanism is symmetrical as to both doors.

Fig. 3 represents two doors A and B hinged to swing away from each other around hinges 40 32 and each carrying a catch 10. From what has been set forth above it will be understood that any person approaching the door A for opening it toward him may do so freely in order to enter the space C between the doors, 45 or pass subsequently through the door B, provided that the door B is closed when the person opens the door A. Likewise any person approaching the door B for opening it toward him may do so freely if the door A is latched, 50 but neither door can be opened when the other is open.

In the modification of Fig. 4, the trip bar 30^a is similar to the bar 30 above described in so far as its length, location, and actuation 55 are concerned, but instead of having a single notch 29, it is provided with two notches 29^a in each of which is fitted a link or strut 24^a pivoted at 27^a, the upper end of each of the links or struts co-operating with the tail end 60 16^a of the tumbler. The operation is the same as above described, namely, when either door is opened and its tumbler is swung away from its abutment 21, such end wiping or striking against the upper end of the strut 24^a will 65 cause the endwise movement of the bar 30^a,

thereby bringing the other strut into positive latching position with respect to the opposite tumbler.

I claim:

1. In a device of the class set forth, the combination with two members adapted to be moved as to open position, of catch mechanism co-operating with said members, permitting either of the members to be moved, said catch mechanism having means actuated by 75 the member moved to render it positively impossible for the second member to be moved after the first has been moved, said means including a catch on the first mentioned member to keep the same closed, an actuator operated by said catch on moving said member, and means actuated by said actuator to lock the second member.

2. In a device of the class set forth, the combination of a pair of doors adapted to be severally opened, of catch mechanism normally holding the doors closed to permit either of them to be opened independently of the other, said catch mechanism including means to positively lock a door from being opened while the other is open, said means including a plurality of actuators, a catch on each door engaging one of said actuators to move the same on opening a door, means operated by the actuator moved to lock the other actuator against movement, and means to return said last mentioned means to initial position on closing said door.

3. In a double acting door latch, the combination of a pair of movable tumblers, a keeper acting between the tumblers and serving normally to prevent positively the movement of both of them at the same time, the keeper, however, permitting the movement of either tumbler to the exclusion of the other and being movable at such time so as to positively prevent the movement of the other tumbler, means for attachment to a pair of doors for severally moving the tumblers, and means actuated by the last mentioned means for the purpose of restoring the keeper to normal position when the doors are both shut.

4. In a double acting door latch of the character set forth, the combination of a pair of tumblers pivoted for swinging movement in spaced relation to each other, a keeper bridging the space between the tumblers and preventing normally the movement of both of them at the same time, but permitting the movement of either to the exclusion of the other, a spring actuated member carried by each tumbler, a member for attachment to a door and co-operating with the catch member of each tumbler and serving to cause the swinging of the tumbler when the door is being opened, means co-operating with each tumbler to restore its normal position after being moved, the catch member on the tumbler and the means carried by the door co-operating to restore the catch means to nor- 120 125 130

mal position when the door is being shut, and means actuated by the door while closing to restore the keeper to normal position.

5. In double acting latch means for a pair of doors, the combination of a pair of tumblers pivoted for swinging movement severally in opposite directions and spaced from each other, a slidable keeper bridging the space between the tumblers, said keeper being movable freely endwise when either

door is opened and the tumbler pertaining thereto is swung around its pivot, a trip bar slidable parallel to the keeper, a pair of catch members for connection to the pair of doors and between which the trip bar normally spans the space, and means to cause slidable movement of the keeper and trip bar severally each from the other, substantially as set forth.

15 In testimony whereof I affix my signature.
CARL JOHN HAGSTROM.
